(57) **CLAIM**

The ornamental design for an electronic cigarette, a component 1 for the electronic cigarette, and a component 2 for the electronic cigarette, as shown and described.

DESCRIPTION

FIG. 1 is a front elevational view of a component 1 for an electronic cigarette showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, right, and top perspective view thereof;

FIG. 8 is a rear, left, and bottom perspective view thereof;

FIG. 9 is a front elevational view of a component 2 for the electronic cigarette showing my new design;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a front, right, and top perspective view thereof;

FIG. 16 is a rear, left, and bottom perspective view thereof;

FIG. 17 is a front elevational view of the electronic cigarette showing my new design in a state where component 1 and component 2 combined;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof;

FIG. 23 is a front, right, and top perspective view thereof; and,

FIG. 24 is a rear, left, and bottom perspective view thereof.

(Continued)

The broken lines in the figures are included for the purpose of illustrating portions of the article which form no part of the claimed design.
